CLAIM

We claim the ornamental design for a universal conduit strap, as shown and described.

DESCRIPTION

FIG. 1 is a top, rear perspective view of a universal conduit strap in accordance with our new design. The design illustrates a rigid arm with a fastener opening, a retention portion having a split-arm configuration, the split arm comprising a flexible arm capable of accommodating multiple diameters of conduit, and two rigid retention arms. The design is shown in an unflexed biased position;

FIG. 2 is a left-side elevation view thereof;

FIG. 3 is a right-side elevation view thereof;

FIG. 4 is a top plan view thereof;

FIG. 5 is a bottom plan view thereof;

FIG. 6 is a front elevation view thereof;

FIG. 7 is a rear elevation view thereof;

FIG. 8 is a bottom, front perspective view thereof;

FIG. 9 is a top, rear perspective of the universal conduit strap illustrating the strap securing a first smaller sized conduit, (e.g. smaller diameter conduit) to a work surface. The flexible arm is biased inward in the unflexed position when retaining the smaller conduit;

FIG. 10 is a right side elevation view thereof;

FIG. 11 is a top, rear perspective of the universal conduit strap illustrating the flexible arm biased outwards in a flexed position for retaining a larger conduit; and,

FIG. 12 is a right side elevation view thereof.

The broken lines in the drawings depict environment of the universal conduit strap that form no part of the claimed design.
